UNITED STATES PATENT OFFICE.

WILLIAM J. PIERCE, OF EUREKA, CALIFORNIA.

BED-CASTER.

1,063,727.

Specification of Letters Patent. Patented June 3, 1913.

Application filed July 31, 1912. Serial No. 712,462.

To all whom it may concern:

Be it known that I, WILLIAM J. PIERCE, a citizen of the United States, residing at Eureka, in the county of Humboldt and 5 State of California, have invented new and useful Improvements in Bed-Casters, of which the following is a specification.

This invention relates to casters and particularly to casters for beds and other furniture.

10 It is an object of the present invention to provide a bed caster having a roller connected to a stem which is turnable in a bearing formed of a cup-shaped piece, within which 15 is mountable an elastic inverted socket spring; the purpose of the peculiar shape of the cup member and spring being to more substantially support the foot of the bed and guide and brace the roller spindle.

20 The invention consists of the parts and the construction and combination of parts as hereinafter more fully described and claimed, having reference to the accompanying drawings, in which—

25 Figure 1 is a perspective view of the caster showing the bed post in dotted lines. Fig. 2 is a central vertical section through the device applied to a bed post.

In the illustrated embodiment of the invention 30 2 represents a roller having a spindle 3 which is journaled in a suitable bifurcated bearing 4, to which is rigidly secured an upwardly projecting stem or spindle 5 adjacent the lower end of which may 35 be formed a washer or collar 6. The spindle 5 is of sufficient length to project upwardly through a cup-shaped member 7, centrally perforated, as at 8, to admit the stem 5; the lower portion of the cup or 40 socket piece 7 bearing upon the washer 6 on the bearing 4. The stem 5 projects upwardly through the cup socket 7 and extends somewhat beyond or above a spring structure 9, which has a diaphragm or cross plate 45 10, centrally perforated, as at 11, to admit the end of the stem 5; the side arms 12 of the spring device extending downwardly and normally expanding so as to engage the walls of the cup socket 7, and the lower ends 50 of the leaves 12 of the spring expanding and being turned slightly outward, as at 13.

The upper end of the spindle 5 is perfor-

ated diametrically, as at 14, to receive a cotter pin or other suitable device 15, which may be passed through the eye of the spindle 5 after the parts have been assembled, as shown in Fig. 1. In the case of fracture or injury of any of the parts, the cotter pin or locking device 15 may be removed so that the broken or injured piece may be removed and a new one substituted in lieu thereof.

In practice, the caster structure is made of various designs and proportions, so that one or the other may be applied to the foot 65 structure A of a bed or other article of furniture to which the caster may be applied. The space between the inner surface of the socket walls 7 and the outside surfaces of the leaves 12 is designed to be sufficient to permit the insertion of the leg or post A, and as the spring piece 10—12 is forced into the post A, the leaves of the springs will automatically yield and frictionally bind themselves in the post A, while the collar or 70 cup structure 7 will slide over the circumference of the post structure A, until the transverse end of the latter sets on the outwardly turned portions 13 of the spring 12, which will then be forced firmly down upon the bearing or supporting cup 7, this in turn transmitting the load of the article to be supported to the roller 2 of the caster.

From the foregoing it will be seen that the caster is braced against tilting or buckling by reason of the snug fit of the socket or cup 7 over the end of the post A, while the 85 caster structure is removably but firmly secured in position by reason of the spring structure 10—12.

Manifestly the device may be made of various styles, shapes and sizes, and of any suitable material.

Having thus described my invention, what I claim and desire to secure by Letters Patent is—

In a caster of the character described, a rectangular casing adapted to inclose the lower end of a square post, which has a square inwardly tapering opening in its lower end, a central cup fitting said opening and having a central perforation at the top, the rectangular sides of which cup are flanged outwardly at the bottom to fit with-

in the casing, and upon which flange the bottom of the post rests, and is clamped between the interior cup and the casing, said casing having a hole in the bottom register-
5 ing with that in the top of the cup, and adapted to receive the spindle of a roller caster.

In testimony whereof I have hereunto set my hand in the presence of two subscribing witnesses.

WILLIAM J. PIERCE.

Witnesses:

J. J. CAIRNS,

WILLIAM KEHOE.
